RECORDING THERMOMETER OR THE LIKE

George A. Argabrite, Malibu, Calif., assignor to Pacific Transducer Corporation, Los Angeles, Calif., a corporation of California

Filed Feb. 2, 1960, Ser. No. 59,240

Term of patent 14 years

(Cl. D52—7)

FIG. 1.

FIG. 2.

FIG. 3.

Fig. 1 is a front perspective view of a recording thermometer showing my new design;

Fig. 2 is a side view thereof; and

Fig. 3 is a rear view thereof.

I claim:

The ornamental design for a recording thermometer or the like, substantially as shown.
